UNITED STATES PATENT OFFICE.

GEORGE E. LINDBERG, OF DULUTH, MINNESOTA, ASSIGNOR TO DIAMOND CALK HORSE SHOE CO., OF DULUTH, MINNESOTA, A CORPORATION OF MINNESOTA.

HORSESHOE.

1,320,878.

Specification of Letters Patent.

Patented Nov. 4, 1919.

Application filed February 19, 1915. Serial No. 9,272.

To all whom it may concern:

Be it known that I, GEORGE E. LINDBERG, a citizen of the United States, residing at Duluth, in the county of St. Louis and 5 State of Minnesota, have invented certain new and useful Improvements in Horseshoes; and I do declare the following to be a full, clear, and exact description of the invention, such as will enable others skilled 10 in the art to which it appertains to make and use the same.

It is desirable in fitting shoes to horses that the calks of the shoe be set at different angles or different positions for different 15 horses. This is for the reason that with some horses the toe and heel calks, to best adapt the shoe to the horse, should be set at right angles to the body of the shoe, while with others, where the horse has a 20 tendency to throw its feet outwardly, or "interfere", i. e., strike the hoof of one foot against the opposite foot, it is desirable that the heel calks be set obliquely. Oftentimes these different tendencies of a horse are not 25 known at the time of fitting and nailing the shoe to its foot, and in other cases, the shoe may be adapted to a horse at the time it is fitted and nailed but the horse later acquires the habit of "interfering" or throwing its feet 30 outwardly, which makes it necessary to refit the shoe or calks thereof. With the shoes now in use, it would be necessary to either remove the shoe and replace it with an entirely new one, or to remodel or recast the 35 old shoe or calks thereof.

It is the object of my invention to provide a horseshoe and calks therefor so designed that the calks may be readily removed and set to or at different angles 40 to fit a shoe of the proper size to different horses, or rather to adapt a shoe of the desired size to different horses.

The above and other features of novelty, advantages and capabilities will become 45 apparent from a detailed description of the accompanying drawings in which I have illustrated two practical embodiments of the invention, but the constructions shown therein are to be considered as illustrative 50 only and not as defining the limits of the invention.

Figure 1 is a bottom view of a horseshoe embodying one form of my invention showing the heel calks removed;

Figs. 2 and 3 are detailed views of the 55 calks and opening in the shoe shown in Fig. 1; and

Figs. 4 and 5 are modifications of the same.

In the drawings, the shoe 10 illustrated 60 is shown with the toe calks 11 in place while the heel calks are removed.

The shoe is provided with an opening for each calk, which openings are adapted to receive the shank 12 of the calk. In the form 65 shown in Figs. 1, 2, and 3, the openings in the shoe are provided with an integral spline 13 adapted to fit into any one of the plurality of grooves 14 formed in the periphery of the shank of the calk. By providing the opening with a spline and the shank of the calks with a plurality of grooves as shown, the calks may be adjusted 70 to different positions to properly fit and adapt a shoe of the proper size to different 75 horses.

In the modification shown in Figs. 4 and 5, this same result is accomplished by providing the opening in the shoe with a plurality of grooves 15 and the shank of the 80 calk with a spline 16, which spline is adapted to fit into any one of said grooves when the calk is inserted in its position.

My invention is capable of other modifications than the two forms illustrated in 85 the drawings and hereinbefore specially described, but I do not wish to be understood as limiting myself to the specific forms shown, except in those claims where these features are specified.

Having thus described my invention, what I claim is:

1. A horseshoe having an opening therein for receiving the shank of a calk, a spline formed in said opening, a calk provided 95 with a shank adapted to fit into said opening and be removable therefrom, said shank having formed around its circumference a plurality of longitudinally extending grooves adapted to receive said spine, the 100 number of said grooves being such as to adapt said calk to be readily adjusted to various angular positions with relation to said shoe.

2. A horseshoe having an opening therein 105 for receiving the shank of a calk, a calk provided with a shank adapted to fit into said opening and be removable therefrom,

one of said interfitting parts having formed around its circumference a plurality of longitudinally extending grooves at intervals less than 180° , and the other of said interfitting parts having formed thereon a spline, said grooves being adapted to receive said spline, the number of said grooves being such as to adapt said calk to be readily adjusted to various angular positions with

relation to said shoe and differing one from another by less than 90° .

In witness whereof, I hereunto subscribe my name to this specification in the presence of two witnesses.

GEORGE E. LINDBERG.

Copies of this patent may be obtained for five cents each, by addressing the "Commissioner of Patents, Washington, D. C."

It is hereby certified that in Letters Patent No. 1,320,878, granted November 4, 1919, upon the application of George E. Lindberg, of Duluth, Minnesota, for an improvement in "Horseshoes," an error appears in the printed specification requiring correction as follows: Page 1, line 100, claim 1, for the word "spine" read *spline*; and that the said Letters Patent should be read with this correction therein that the same may conform to the record of the case in the Patent Office.

Signed and sealed this 6th day of January, A. D., 1920.

[SEAL.]

M. H. COULSTON,
Acting Commissioner of Patents.
